CLAIM

The ornamental design for a well plate for assays as shown and described.

DESCRIPTION

FIG. 1 is a top perspective view of a well plate for assays showing the new design;

FIG. 2 is a bottom perspective view thereof;

FIG. 3 is a top plan view thereof;

FIG. 4 is a back elevational view thereof;

FIG. 5 is a right elevational view thereof;

FIG. 6 is a front elevational view thereof;

FIG. 7 is a left elevational view thereof;

FIG. 8 is a bottom plan view thereof; and,

FIG. 9 is a cross sectional view thereof.

The broken lines in the drawings depict environmental subject matter and form no part of the claimed design.
